UNITED STATES PATENT OFFICE.

ARCHIE M. JOLIVETTE, OF GREENFIELD, MASSACHUSETTS.

HAND OR MAN HOLE COVER.

1,194,295.

Specification of Letters Patent.

Patented Aug. 8, 1916.

Application filed September 8, 1915. Serial No. 49,595.

To all whom it may concern:

Be it known that I, ARCHIE M. JOLIVETTE, a citizen of the United States, residing at Greenfield, in the county of Franklin and State of Massachusetts, have invented certain new and useful Improvements in Hand or Man Hole Covers; and I do hereby declare the following to be a full, clear, and exact description of the invention, such as will enable others skilled in the art to which it appertains to make and use the same.

My invention relates to improvements in hand or manhole closures for steam boilers, tanks, or other like vessels, and it is intended to provide a simplified form of construction which will adapt itself to the conditions required, and may be readily applied or removed as desired.

My invention comprises a cast metal plate recessed to receive the inner end or head of a T-shaped bolt, and consists of certain novel features which will be hereinafter described; reference being had to the accompanying drawings, in which the same parts are indicated by similar reference symbols throughout the several views:—

Figure 1 is a front elevation of the manhole plate in place, showing the yoke and bolt in section along the line 1—1 of Fig. 2, and looking in the direction of the arrows; Fig. 2 shows a section along the line 2—2 of Fig. 1 looking down, parts being shown in elevation and parts broken away; Fig. 3 is a detail showing the chambered plate or cover; and Fig. 4 is a detail showing one of the bolts with the elongated heads used in combination with the plate.

A represents a boiler having the usual manhole or hand hole a and B represents the manhole plate or cover which is preferably in elliptical form, as shown, the outer ellipse B' being larger than the elliptical boss B^2 , which is concentric therewith, and exterior to this boss B^2 is a plain surface b for the gasket C.

The elliptical boss B^2 is provided with an elongated recess b' projecting down to the plane of the face b , and opening outward through the sides of the elliptical boss are two wing chambers b^2 and b^3 in the staggered relation as shown in Figs. 1 and 3.

The bolt D is provided with the usual washer d and usual nut d' , and has on its inner end an elongated head D' , which is substantially rectangular in form, as shown in Figs. 1 and 4.

E represents the yoke of any suitable or desired construction.

To apply the device the head D' of the bolt is inserted in the rectangular recess b' and is then turned in clockwise direction to engage in the wing chambers b^2 and b^3 ; this turning movement being arrested by the walls b^4 and b^5 of said wing chambers. Now the cover may be very readily inserted in the opening a , and the yoke, washer and nut may be readily applied.

To remove the parts apply a wrench in the usual way to the nut d' tending to unscrew the same, and if this nut is rusted to the screw as frequently happens, before the nut will yield the bolt will itself turn until the head D' of the bolt will register with the opening b' in the plate, and the bolt may be readily withdrawn and with it the yoke E, leaving the plate in place to be removed by hand.

It is not necessary to have any special nice adjustment of the parts, as it is desirable to have the bolt free to move slightly in any direction, permitting the whole yoke and plate to line up properly against the boiler shell. For this reason there should be a loose fit between the head of the bolt and the recess b' and the wing chambers b^2 and b^3 , and also between the bolt and the yoke.

It will be obvious that the bolts can be easily renewed in old plates, and much time can be saved in removing all the parts from the boiler. It will also be seen that it will not be necessary to cut the nuts off in dark and cramped quarters, as frequently happens with the present style of bolt.

To operate the device only the usual wrench is needed, and if the nut sticks fast it can be very readily loosened where there are suitable facilities for so doing and where there is plenty of elbow room.

While I have shown the bolt head and recess and wing chambers as rectangular in shape, and I prefer that they should be substantially rectangular, it will be obvious that other suitable shapes may be adopted, if desired.

It will be obvious that the hand or manhole closures constructed as hereinbefore described may be very quickly and conveniently applied and readily and conveniently removed when desired.

While the device is especially adaptable for manhole closures, it is also applicable

to hand hole closures and I do not mean to limit the invention to any particular closure for an opening in any particular vessel adapted to withstand steam or other fluid pressure.

Having thus described my invention what I claim and desire to secure by Letters Patent of the United States is:—

1. In a man or hand hole closure for boilers, the combination with an elliptical plate provided with an elliptical boss projecting inwardly therefrom, and a bearing surface for the gasket exterior to said elliptical boss, the said boss having a rectangular central recess in the inner wall thereof and two laterally-disposed wing chambers opening through the sides of said boss arranged in staggered relation and connected interiorly with said central recess, of a T-shaped locking bolt provided with a laterally elongated rectangular head adapted to pass through said recess, and to engage, when turned through an angle, with said laterally-disposed wing chambers, and means for con-

necting said bolt to the boiler, substantially as described.

2. In a man or hand hole closure for boilers, the combination with an elliptical plate provided with an elliptical boss projecting inwardly therefrom, and a bearing surface for the gasket exterior to said elliptical boss, the said boss having a rectangular central recess in the inner wall thereof and two laterally-disposed wing chambers opening through the sides of said boss arranged in staggered relation and connected interiorly with said central recess, of a T-shaped locking bolt provided with a laterally elongated rectangular head adapted to pass through said recess, and to engage, when turned through an angle, with said laterally-disposed wing chambers, and a yoke and nut for connecting said bolt to the boiler, substantially as described.

In testimony whereof, I affix my signature.

ARCHIE M. JOLIVETTE.
